UNITED STATES PATENT OFFICE.

MAURICE MATHY, OF LIEGE, BELGIUM.

COKE-OVEN.

1,392,257.

Specification of Letters Patent. Patented Sept. 27, 1921.

Application filed July 17, 1919. Serial No. 311,609.

To all whom it may concern:

Be it known that I, MAURICE MATHY, a subject of the King of Belgium, and resident of Liege, in the Kingdom of Belgium, have invented certain new and useful Improvements in and Relating to Coke-Ovens; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

15 This invention relates to improvements in coke ovens having means for recovering the by-products.

According to the present invention the retort is heated by surface combustion methods. 20 This result is realized by providing beneath each retort a passage in which the mixture of air and gas takes place, said mixture then penetrating into various vertical flues arranged in the jamb columns of 25 the retort filled with porous and fireproof material. The hot gas released from the upper part of these flues is brought by other like flues, but which are not filled with porous material, into a recuperator serving 30 for heating air and and gas or only one of these fluids. Two recuperators of this kind are arranged under each retort.

The invention is more particularly described with reference to the accompanying 35 drawings showing as an example a form of construction in the case of a recuperator which only heats air.

Figure 1 is a transverse section of the bed or brick work in the axis of the retort.

40 Fig. 2 is a section on the line A B of Fig. 1.

Fig. 3 is a section on the line I J K L of Fig. 2.

Fig. 4 is a section on the line C D of 45 Fig. 1.

Fig. 5 is a horizontal section on the line E F of Fig. 4.

Fig. 6 is a horizontal section on the line G H of Fig. 2.

50 Beneath each retort 1 a pair of suitable recuperators 2 is arranged: in the the form of construction illustrated earthenware or fireclay recuperators are used. Each of these

recuperators receives hot gas from one-half of the retort and heats the air for this portion of the retort.

In the jamb columns on each side of and extending over one-half of the retort, vertical flues 3 and 4 are arranged.

The flues 3, that is to say, those on the side of the masonry face, are filled with porous and refractory material and serve for heating the retort.

The flues 4, that is to say, those arranged toward the center of the foundation or brick work, serve for conveying the gases of combustion to the recuperator.

All the flues 3 and 4 of the same half retort situated in the same jamb are connected at their upper part by a common horizontal flue 5. At their lower part the flues 3 end in a horizontal flue 6, while the flues 4 end in a vertical flue 7. (See particularly Fig. 6.)

This flue 7 communicates with a flue 22 conveying the hot gas to the recuperator 2. Beneath the bed of each retort are arranged two superimposed passages 8 and 9.

The first passage 8 is fed with gas by the pipe 10. The second passage 9 is fed with hot air by the vertical passages 11 connecting with a passage 12 receiving hot air from the recuperator 2.

At the sides of the passages 8 and 9, other passages 13 and 14 communicating with the passages 8 and 9 by vertical slots 15 and 19, are arranged, and these passages 8 and 9 are preferably constructed by means of fireclay or firebrick elements.

The passages 13 and 14 communicate with the flues 6 and are like them and like the vertical flues 3, filled with porous and refractory material.

Cold air from a pipe 16 is conveyed for each retort by a pipe 17 into a chamber 18 from which it passes into the recuperator 2. After having been heated in this recuperator it penetrates into the passage 12 and goes by the various passages 11 into the passage 9. It flows through the various vertical slots 19 in this passage and encounters in the passages 13 and 14 in the center of the mass of porous and refractory material which is found there the gas emerging from the vertical slots 15 of the passage 8.

It is preferable that the slots 15 and 19 ending at a common passage 13 or 14 shall not be in the same vertical plane but be staggered relatively to one another.

5 The mixture of gas and air which is there produced ignites and enters the flues 6 and then passes into the vertical flues 3, thus causing the heating of the retort.

The hot gas which is discharged from the 10 upper part of the flues 3 is collected in the flue 5. It then passes into the vertical flues 4 and is led by the flue 22 to the recuperator 2. After having heated the air brought into this recuperator it is conveyed by a channel 15 20 to the gallery 21.

Having now particularly described and ascertained the nature of the said invention and in what manner the same is to be performed, I declare that what I claim is:—

20 1. A coke oven comprising retorts, flues

on each side of said retorts, filled with porous and refractory materials and means for conveying a mixture of air and gas for surface combustion inside said flues.

2. A coke oven comprising retorts, flues on 25 each side of said retorts, filled with porous and refractory materials a pair of parallel passages arranged under each retort for air and gas respectively, and parallel ducts on the side of said passages, filled with porous 30 and refractory materials and communicating on the one hand with the flue and on the other hand with the parallel passages.

In testimony whereof I affix my signature in presence of two witnesses.

MAURICE MATHY.

Witnesses:
